UNITED STATES PATENT OFFICE.

GOTTHILF ANSGARIUS BETULANDER, OF SÖDERTÖRNS VILLASTAD, AND NILS GUNNAR PALMGREN, OF STOCKHOLM, SWEDEN, ASSIGNEES, BY DIRECT AND MESNE ASSIGNMENTS, TO THE BETULANDER AUTOMATIC TELEPHONE COMPANY, LIMITED, OF LONDON, ENGLAND.

AUTOMATIC TELEPHONE-EXCHANGE SYSTEM.

1,195,771.

Specification of Letters Patent. Patented Aug. 22, 1916.

Original application filed December 20, 1913, Serial No. 807,925. Divided and this application filed May 12, 1915. Serial No. 27,685.

To all whom it may concern:

Be it known that we, GOTTHILF ANSGARIUS BETULANDER, a subject of the King of Sweden, and resident of Villa Castor, Södertörns 5 Villastad, in the Kingdom of Sweden, and NILS GUNNAR PALMGREN, a subject of the King of Sweden, and resident of Björnsgårdsgatan 3, Stockholm, in the Kingdom of Sweden, have invented certain new and useful 10 Improvements in or Relating to Automatic Telephone-Exchange Systems, of which the following is a specification, reference being had therein to the accompanying drawings.

15 The invention relates to an automatic telephone exchange system such as is described in the copending application Serial No. 807,925, filed December 20th, 1913, of which the present application is a division.

20 The main object of the invention is to provide means for effecting the connections in such systems by means of relays only.

25 The accompanying drawings illustrate circuit arrangements according to this invention for effecting connections between the incoming and outgoing lines of a group selecting section over intermediate lines arranged in the manner described in said application No. 807,925.

30 Figure 1 shows the arrangement between the incoming junction lines and the intermediate lines. Fig. 2 shows two group selectors which are common to all incoming junction lines. Fig. 3 shows the arrangement between the intermediate lines and the outgoing junction lines together with a testing device.

35 For simplicity only three of the incoming junction lines 111, 112, Fig. 1, are represented. Each junction line 111, 112 is adapted to be connected by means of relays 113 and through contacts 116, 117 to any one of the intermediate lines 114, 115 only three of which are shown in the drawing. Besides, each incoming junction line 111, 112 is adapted to be connected by means of two relays 118 and 119 and through contacts 122, 123 with one or the other of the group-selectors 120 and 121, Fig. 2. The latter 45 are composed of relays only and consist of a series of selecting relays 124 and a series of auxiliary relays corresponding to the

several selecting relays. Each series comprises as many relays as there are groups of outgoing junction lines, thus, usually ten relays. Only three relays are shown in the drawing corresponding to the three groups I, II, III, Fig. 3, of outgoing junction lines. For the purpose of controlling the shifting operation and the emission of currents 55 relays 126, 127, 118 and 172 are allotted to each group-selector. In addition, two relays 129 and 130, Fig. 1, are provided the object of which is to mark the corresponding group-selector as engaged during the shifting period.

Each intermediate line 114, 115, Fig. 3, is provided with three relays 131 by means of which it may be connected with one junction line 132, 133 in each group I, II and III 70 through contacts 134, 135. Thus, the upper intermediate line 114, 115 is arranged to be connected with the first junction lines of the said groups, the middle intermediate line to be connected with the second junction lines 75 and the lower intermediate line to be connected with the third junction lines.

The object of the testing device shown to the right in Fig. 3 is to test all the junction lines of the group selected by the group-selector and to control the operating circuits of the connecting relays 113 and 131 so that, in the moment of establishing the connection, only those relays corresponding to an outgoing junction line at the time available 85 are operated. The testing device consists of a series of testing relays 136 provided with two windings 137, 138, and of a series of switching relays 139 corresponding to the several testing relays. Each series comprises as many relays as there are junction lines 132, 133 in each group I, II, III, thus, in this case three relays. The testing device is adapted to be connected with the test wires of the junction lines 132, 133 of any 95 selected group I, II or III through contacts 140 of relays 141 operated from the group-selector. A relay 142 is provided to effect the final emission of those current impulses by which the connecting relays 113 and 131 100 are operated. The relay 143 operates to prevent the group-selectors from simultaneously actuating the testing device, as will be explained more closely below.

The connecting relays 113 and 131 are provided with two windings 144 and 145 the first 144 of which has for its object to effect the attracting of the armature while the other 145 only serves to hold the armature in attracted position. The windings 144, which may be called operating windings, are connected at one side with wires extending along the different horizontal rows 10 of relays and at the other side with wires extending along the different vertical rows of relays. Accordingly, in Fig. 1 the operating windings 144 of relays 113 pertaining to a horizontal row are connected in parallel with a corresponding horizontal wire 146 while the windings 144 of relays pertaining to a vertical row are connected in parallel with a corresponding vertical wire 147. The relays are thus interposed in the 20 crossing points of the different horizontal and vertical wires 146 and 147 and may be operated by connecting the corresponding horizontal and vertical wires to opposite poles of the battery. In a similar manner 25 the operating windings 144 of the relays 131, Fig. 3, are connected with horizontal and vertical wires 148 and 149.

A third wire (holding or releasing wire) 150 and 151 respectively, Fig. 1, and 152 and 30 151 respectively, Fig. 3, extends along the different junction lines and the intermediate lines. When the connecting relays 113 and 131 attract their armatures the locking windings 145 are connected in series with 35 the said wires through contacts 153 and are then maintained current-carrying through these wires during the duration of the existing interconnection.

The intermediate lines 114, 115 are provided with test wires Fig. 3, which, when the corresponding intermediate lines are engaged, are connected to earth through a contact 155 of a corresponding connecting relay 131. The outgoing junction lines 132, 45 133 have similar test wires 156 which may be connected to earth through contacts 157 of the connecting relays 131.

As to the reference numerals it will be noted that similar relays and lines pertaining to the same group of relays as also corresponding relay contacts and windings are designated by the same reference numerals. In order to distinguish similarly designated 50 relays, the relays provided in the same vertical row are called the "upper", "middle" and "lower" relay respectively and the relays provided in the same horizontal row are called the "first", "second" and "third" relay respectively counted from the left to the right. Thus, for instance, the third connecting relay 113, Fig. 1, from the left of the middle horizontal row is called the "third middle" relay 113.

In the moment of the connection of a subscriber's line with an incoming junction

line 111, 112, for instance the upper one of Fig. 1, a circuit is closed extending from earth at the appertaining wire 150 through this wire, the contacts 158 of the connecting relays 113 and further, if the first group-selector 120 is disengaged, through contact 159 of relay 119, winding 160 of relay 118 and contact 161 of relay 129 to the battery. The relay 118 is energized upon the closure of that circuit whereby the junction line 111, 70 112 is connected to the first group-selector 120 through the contacts 122, 123 and the line 162, 163. In the next moment both line branches 111, 112 are connected to earth in any preferable manner by means of the ordinary set of repeating relays (not shown) operated from the calling substation, a circuit being thereby closed extending from earth through the line branch 112, contact 122 of relay 118, wire 162, contact 164 of relay 127, Fig. 2, and further partly through the relay 126, partly through the wire 165 and the winding 166 of the relay 129, Fig. 1, to the battery. The relay 129 thereby energizes and marks the appertaining group-selector as engaged by opening the contact 161. The relay 126, Fig. 2, also operates and cuts itself in a locking circuit through its contact 167. The relay 127 simultaneously receives current through the contact 168 of the relay 126. The relay 127, upon operating, closes a circuit extending from earth at the said relay through contact 169, wire 170 and winding 166 of relay 129, Fig. 1, to the battery. Consequently, the armature of the relay 129 is maintained in attracted position as long as the relay 127 is energized. The latter has cut itself in a locking circuit through its contact 173 and the contact 174 of the relay 128. Upon the energizing of the 100 relay 129 the winding 175 of the relay 118, Fig. 1, is also cut in a locking circuit through the contact 176 of the same relay and the contact 177 of the relay 129. The relay 129 simultaneously closes its contact 178 so that, 110 hereafter, the relay 119 may be used to connect another junction line 111, 112 with the second group-selector 121.

Through the energizing of the relay 126, Fig. 2, a circuit is closed extending from earth at the line branch 111, Fig. 1, through this line branch, the contact 123 of the corresponding relay 118, wire 163, contact 179 of relay 126, Fig. 2, contact 180 of the first, lower relay 124 of the group-selector 120 120 and the corresponding auxiliary relay 125 to the battery. The relay 125 is thereby energized and cuts in the corresponding relay 124 through the contact 181. The relay 124, upon energizing, cuts itself in a locking circuit through its contact 182 and the contact 169 of the relay 127. The auxiliary relay 125 is simultaneously cut in a locking circuit through the contact 183 of the relay 124 and the contact 184 of the relay 125. Through 130

the action of the number switch of the calling subscriber the current flowing in the line branch 111 is now broken and closed a certain number of times while the line branch 112 is maintained current-carrying. If, for instance, connection with a line of the third group III is desired the said current is interrupted three times. Upon the first interruption the auxiliary relay 126 releases its armature. Consequently, the next current impulse in the line branch 111 passes through the contact 183 of the first selecting relay 124, the contact 185 of the corresponding auxiliary relay 125, the contact 180 of the second selecting relay 124 and the corresponding auxiliary relay 125 to the battery. The second relays 124 and 125 are thereby operated in the same manner as the corresponding first relays. The third impulse operates the third relays 124 and 125 in the same manner. Thereupon the currents of both line branches 111 and 112 are interrupted the third auxiliary relay 125 then releasing its armature. Simultaneously, the relay 126 deenergizes thereby closing a circuit extending from earth through the contact 186 of the relay 126, contact 187 of relay 127, contact 188 of relay 172 and further parallelly partly through the wire 189 and the relay 172 of the group-selector 121, partly through the contacts 190 of the relay 124 of the group-selector 120, wire 191, wire 149 and the third, lower relay 141, Fig. 3, to the battery. The relay 172 of the group-selector 121, Fig. 2, energizes upon the closure of that circuit thereby preventing the group-selector 121, if this one is simultaneously operating, from affecting the testing device, Fig. 3, at the same time as the group-selector 120, as will be explained more closely below. Further, the third group-relay 141, Fig. 3, energizes and connects the test wires 156 belonging to the junction lines 132, 133 of the third group III through the contacts 140 of the relay 141 to the windings 137 of the testing relays 136.

Supposing now that the first junction line 132, 133 of the third group III is engaged, a circuit is then closed extending from earth at the corresponding relay 131 through contact 157, test wire 156, wire 192, the corresponding contact 140 of the third relay 141 and the winding 137 of the first testing relay 136 to the battery. The relay 136 is thereby energized. If at the same time for instance the second intermediate line 114, 115 is used for a connection in another group there is a current flowing from earth at a corresponding connecting relay 131 through the contact 155 of that relay, the corresponding wire 154 and the winding 138 of the second testing relay 136 to the battery. Consequently, the armature of the relay last mentioned is attracted. Thus, in this instance, connection may be obtained only

with the third junction lines 132, 133 of the third group.

In order that the relay 136 may be energized only in the moment of the testing of the junction lines a contact may be provided between the said relay and the negative pole of the battery said contact being controlled by a relay operated from the group-selector, so that also the windings 138 may be currentless when the testing device is disengaged. 75

Upon the energization of the relay 141 the current emitting relay 142 is cut in at the contact 193 of the relay 141. The relay 142, upon energizing, closes a circuit extending from earth through the third switching relay 139, the contact 194 of the third testing relay 136, the contact 195 of the third switching relay 139, the contact 196 of the second testing relay 136, the contact 195 of the corresponding switching relay 139, the contact 196 of the first testing relay 136, the contact 195 of the corresponding switching relay 139 and the contact 197 of the relay 142 to the battery. Upon the closure of that circuit the third switching relay 139 cuts itself in a locking circuit through its contact 198. At the same time the following two circuits are closed: *a*, from earth at the relay 126, Fig. 2, through contacts 186, 187, 188, 190, wire 191, wire 149, Fig. 3, winding 144 of the third, lower connecting relay 131, the corresponding wire 148, contact 199 of the third switching relay 139, contacts 196, 195, 196, 195 of the second and first relays 136 and 139 and contact 197 to the battery; *b*, from earth at the relay 126, Fig. 2, through contacts 186, 187, 188, wire 200, contact 201 of the upper relay 118, Fig. 1, the corresponding wire 146, winding 144 of the third, upper connecting relay 113, the corresponding wire 147, the corresponding wire 148, Fig. 3, contact 199 of the third switching relay 139, contacts 196, 195, 196, 195 of the second and first relays 136 and 139 and contact 197 to the battery. Upon the closure of these circuits the third, upper connecting relay 113, Fig. 1, and the third, lower connecting relay 131, Fig. 3, are energized the first incoming junction line 111, 112, Fig. 1, being thereby connected to the third outgoing junction line 132, 133 of the third group III through the third intermediate line 114, 115. At the same time a locking circuit for the said connecting relays is closed from earth at the releasing wire 150 of the first incoming junction line 111, 112 through this wire 150, the locking winding 145 of the third, upper connecting relay 113, contact 153, the corresponding wire 151, the locking winding 145 of the third, lower connecting relay 131, Fig. 3, contact 153, the corresponding wire 152 and further to the battery in any preferable manner, for instance as shown at the wire 150, Fig. 1. 120

Upon the energization of the relay 142, Fig. 3, also the relay 143 is cut in through the contact 197. At the same time as the above mentioned circuits *a* and *b* were closed another circuit is closed by the relay 143 extending from earth through contact 202 of said relay, wire 203, wire 204, Fig. 2, contact 205 of the relay 172 belonging to the group selector 120, and the relay 128 to the battery. Consequently, the relay 128 is energized and the locking circuit of the relay 127 is broken the latter thereby releasing its armature so that the circuits *a* and *b* stated above as well as the circuit of the relay 129, Fig. 2, the circuit of the relay 172 of the group selector 121, Fig. 2, and the circuit of the relay 141, Fig. 3, are interrupted. When the relay last mentioned releases its armature also the relays 142, 143, 136, 129 and 128 are made currentless. As the relay 129, Fig. 1, releases its armature the relay 118 is deprived of current so that the group selector 120 is separated from the incoming junction line 111, 112. Consequently, this group selector as well as the testing device, Fig. 3, are now disengaged and may be used for effecting another connection. In that case when one subscriber is actuating for instance the group-selector 120 and then another subscriber connects his line with an incoming junction line 111, 112, Fig. 1, the corresponding relay 119 receives current through the corresponding wire 151, contact 158 of relay 113, contact 159 of relay 118, winding 160 of relay 119, contact 161 of relay 139 and the contact 173 of relay 129. The relay, upon operating, connects the line 111, 112 in the manner previously described with the group-selector 121. As the relay 139 then attracts its armature the winding 175 of the relay 119 is cut in circuit through the contact 177 of the relay 139 and the contact 176 of the relay 119. Both group selectors may now be operated simultaneously. However the selectors must not split the testing current through the contact 199 at the same moment. This is prevented by means of the relay 172 inasmuch as that selector the relay 128 of which is first deenergized operates the relay 172 of the other selector in the manner described above so that the contact 188 is opened. The said relay 172, by opening the contact 205, simultaneously prevents the operation of the relay 128 at the same time as the corresponding relay of the selector first mentioned. If both relays 120 simultaneously deenergize, at first both relays 172 are energized, the relay 172 of the group-selector 121 thereby cutting itself in a locking circuit through its contact 206, the contact 187 of the relay 127 of the group-selector 120 and the contact 186 of the relay 126. Consequently, the relay 172 of the group selector 121 keeps its armature attracted while the relay 172 of the group selector 120 again releases its armature since its circuit is broken at the contact 188 of the relay first mentioned. The testing device is thus first operated by the group-selector 120. After the connection has been established the relay 128 of the group-selector 120 is operated so that the relay 127 releases its armature thereby breaking the circuit of the relay 172 of the group-selector 121. As the relay last mentioned releases its armature the testing device is operated by the corresponding group-selector 121.

Having now described our invention, what we claim as new and desire to secure by Letters Patent is:

1. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting means for effecting the connections at both ends of the intermediate lines, operating circuits for said connecting means and testing relays controlling said circuits and adapted to select connecting means corresponding to an available intermediate line.

2. A telephone exchange system having in each group-switching section a plurality of numerical groups of outgoing lines; a number of incoming lines each adapted to be connected with any one of the lines of said groups, intermediate junction lines provided between said incoming and outgoing lines and having at their disposal different lines of each numerical group, connecting means for effecting the connections at both ends of the intermediate lines, operating circuits for said connecting means, testing relays controlling said circuits and adapted to select connecting means corresponding to an available intermediate line and relays for connecting the common testing relays with the test wires of any wanted numerical line group.

3. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting relays for effecting the connections at both ends of the intermediate lines, test wires allotted to the several lines, operating circuits for the connecting relays comprising wires corresponding to the various incoming lines, wires corresponding to the various intermediate lines and wires corresponding to the various outgoing lines, testing relays con-

trolling said circuits and relays for connecting the testing relays with the test wires of the wanted numerical line group as well as with the test wires of the intermediate lines.

5. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting relays for effecting the connections at both ends of the intermediate lines, a plurality of common group selectors and relays for connecting the incoming lines with the selectors.
5. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting means for effecting the connections at both ends of the intermediate lines, two group-selectors common to the incoming lines, two corresponding relays adapted to prevent said selectors from simultaneously operating the connecting means and means for opening the circuit of one of said relays by operating the other relay.
10. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting means for effecting the connections at both ends of the intermediate lines, a plurality of common group selectors and relays for connecting the incoming lines with the selectors.
15. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting means for effecting the connections at both ends of the intermediate lines, two group-selectors common to the incoming lines, two corresponding relays adapted to prevent said selectors from simultaneously operating the connecting means and means for opening the circuit of one of said relays by operating the other relay.
20. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting means for effecting the connections at both ends of the intermediate lines, a plurality of common group selectors and relays for connecting the incoming lines with the selectors.
25. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting means for effecting the connections at both ends of the intermediate lines, two group-selectors common to the incoming lines, two corresponding relays adapted to prevent said selectors from simultaneously operating the connecting means and means for opening the circuit of one of said relays by operating the other relay.

the intermediate lines, a plurality of group-selectors common to the incoming lines and means for preventing the selectors from simultaneously operating the connecting means.

6. A telephone exchange system having in each group-switching section a plurality of numerical groups of outgoing lines, a number of incoming lines each adapted to be connected with any one of the lines of said groups, intermediate junction lines provided between said incoming and outgoing lines and having at their disposal different lines of each numerical group, connecting means for effecting the connections at both ends of the intermediate lines, two group-selectors common to the incoming lines, two corresponding relays adapted to prevent said selectors from simultaneously operating the connecting means and means for opening the circuit of one of said relays by operating the other relay.

In witness whereof, we have hereunto signed our names.

GÖTHILF ANSGARIUS BETULANDER.
NILS GUNNAR PALMGREN.
